SPRING BOTTOM FOR BEDS

Max Gursky, Bronx, N. Y.

Application February 18, 1932, Serial No. 593,807

3 Claims. (Cl. 5—260)

This invention relates to spring bottoms for beds and the like articles.

An object of this invention is to provide a spring bottom of the character described having highly improved means for retaining a mattress thereon and to prevent the mattress from shifting on the spring.

A further object of this invention is to provide highly improved means for retaining the mattress on a spring bottom, said means being adapted to be incorporated into the spring bottom when manufacturing the same, or made separately and attached to spring bottoms now in use.

A further object of this invention is to provide a neat, strong and durable spring bottom of the character described, provided with my improved mattress retaining means, which shall be comparatively inexpensive to manufacture, comprise few and simple parts, which shall be easy to assemble, attractive in appearance and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a plan view of a spring bottom embodying the invention;

Fig. 2 is a side elevational view of the spring bottom shown in Fig. 1 with a mattress mounted thereon;

Fig. 3 is a fragmentary enlarged, detailed view of the mattress retaining means;

Fig. 4 is a cross-sectional view taken on line 4—4 of Fig. 2;

Fig. 5 is a fragmentary side elevational view of a mattress retaining means illustrating a modified construction;

Fig. 6 is a cross-sectional view taken on line 6—6 of Fig. 5;

Fig. 7 is a fragmentary side elevational view of a mattress retaining means illustrating a further modified construction;

Fig. 8 is a cross-sectional view taken on line 8—8 of Fig. 7;

Fig. 9 is a fragmentary side elevational view of a still further modified construction;

Fig. 10 is a cross-sectional view taken on line 10—10 of Fig. 9.

Fig. 11 is a fragmentary side elevational view of a spring bottom having a pivoted rear portion adapted to be lifted for supporting a person on a bed with the back of the person in inclined position;

Fig. 12 is a view similar to Fig. 11, but showing a modified construction; and

Fig. 13 is an enlarged cross-sectional view taken on line 13—13 of Fig. 12.

Referring now in detail to the drawings, and particularly to Figs. 1, 2, 3 and 4 thereof, 10 designates a spring bottom embodying the invention, here shown in the form of a usual bed spring, and provided with a member 11 embodying the invention for retaining a mattress 12 on said bed spring.

The spring bottom 10 may be of the usual construction and comprises a preferably oblong bottom frame 15 of angular cross-section. Interconnecting opposite sides 16 and 17 of said frame 15 are transverse parallel supporting strips 18 on which the conical foundation springs 19 rest, said springs being interconnected by tie-wires and small coil tension springs in the usual manner. Interconnecting the uppermost convolutions 20 of the springs 19 and extending about the spring bottom, is an oblong shaped frame 21 preferably made of heavy round stock, the attachment between the springs and the frame 21 being effected by clips 22, tie wires or in any other suitable manner. The clips 22 may comprise simply a strip of metal bent around the frame and the adjacent portion of the convolutions 20.

The retaining member 11 may comprise a frame member 24 similar to the frame 21 and disposed parallel thereto, and directly above the latter. The frame 24 may be attached to the frame 21 by means of woven reed 25, preferably wound about the frame members 21 and 24 and about an intermediate reed 26 extending entirely about the member 11. At the points where the clips 22 are located, the reed may be woven only about the upper frame 24 and the intermediate reed frame 26 to provide openings 27 through which the clips 22 extend. This construction also permits tools to be inserted through the opening 27 in applying the clips for effecting the attachment between the frame 21 and the springs 20. Thus the frame members 21 and 24 may be interconnected by the woven reed 25 and the frame member 21 thereafter attached to the upper convolutions 20 of the foundation springs by means of the clips 22.

It will be noted that the member 11 serves to prevent the mattress 12 from shifting about on the spring bottom. The woven reed 25 results in a strong, light and attractive construction and also serves to protect the mattress and provide a soft covering for the metal parts at the upper edge of the spring.

In Figs. 5 and 6 there is shown a retaining member 11a illustrating a modified construction. The member 11a may be made of a pair of frame members 30 and 31 likewise made of round stock and substantially similar to the frame members 21.

and 24. The frame members 30 and 31 are interconnected by woven reed 32 in a manner similar to the reed 25. However, the member 11a may be made separately from the spring bottom and attached to the upper frame portion 21 thereof by means of tie clips 33. In other words, the member 11a may be attached to spring bottoms now in use and having an upper frame member 21. The frame member 21 is thus attached to the upper convolutions 20 of the springs 19 by spaced clips 22 and attached to the lower frame 30 of the member 11a by spaced clips 33. The clips 33 preferably extend through openings 27a formed by weaving the reed 32 only about the upper frame 31 and the intermediate reed frame 34 at spaced points on said member 11a.

In Figs. 7 and 8 is shown a retaining member 11b illustrating another modified construction. The retaining member 11b likewise extends entirely about the spring bottom and may be made of sheet metal and comprises an upstanding wall 40 having an outwardly curved bead 41 at the top edge thereof. The bottom portion 42 of the member 11b is coiled about the frame member 21, thus effecting a strong attachment between said member 11b and said frame member 21. At spaced points thereon the member 11b is provided with cut away portions 44 to permit the clips 22 attaching the frame member 21 to the convolutions 20, to pass therethrough.

In Figs. 9 and 10 there is illustrated still another modified construction. In said figures a retaining member 11d is likewise made of sheet metal and provided with an upper beaded edge 47. The lower edge of said member 11d is coiled about a frame member 49 similar to the frame member 30. The member 11d may be attached to the member 21 of the spring bottom by means of clips 50 similar to the tie clips 33, said member 11d being recessed as at 52 to permit the clips 50 to pass around the frame member 49. In the construction illustrated in Figs. 9 and 10 the frame member 21 is also attached to the convolutions 20 by means of the tie clips 22. Thus the member 11d may be made separately and attached to spring bottoms now in use, and having an upper frame member 21, by means of the tie clips 50.

In Fig. 11 is shown a portion of a spring bottom 50 substantially similar to the spring bottom 10, but having a rear portion 51 pivoted to the front portion 52 in any suitable manner to permit said rear portion to be moved into inclined position. The portions 51 and 52 of said spring bottom may be provided with complementary mattress retaining members 53 and 54 of woven reed or in like manner similarly to the mattress retaining portion 11 shown in Figs. 2, 3, and 4, said members being interpivoted as at 50a and the pivotal points interconnected by a bar 50b. The portion 54 however, is preferably provided with an upper frame 55 made of tubular material. Pivoted to the upper frame 56 of the portion 53 is a rod 57 slidably and loosely received within the tube 55 to permit the portion 51 of the spring bottom to be pivotally moved upwardly. During such pivotal movement, the rod 57 will merely slide into the tube 55. Obviously, the frame member 56 may be made in the form of a tube for receiving a rod pivoted to the frame 55, which may be in such case made of rod stock such as rod 24 shown in Figs. 3 and 4.

In Fig. 12 is shown a still further modified construction. In accordance with this modified con-

struction, the spring bottom 60 may likewise be formed of a front portion 61 and a rear portion 62 pivoted to said first portion in the usual manner and adapted to be lifted into inclined position, said spring bottom portions 61 and 62 being provided with complementary mattress retaining portions 63 and 64 made of sheet material similar to the mattress retaining member 11b shown in Figs. 7 and 8. The portion 63 comprises an upstanding sheet metal wall 65 to which there is attached in any suitable manner, a second sheet member 66 spaced therefrom and parallel thereto, forming a shallow chamber 67. The portion 64 is formed with a sheet metal wall 68 having an extension projecting into said chamber 67. The end of said member 68 is formed with a curved slot 69 for slidably receiving a rivet 70 fixed to said opposite walls 65 and 66.

It will now be noted that as the spring bottom portion 62 is pivoted upwardly, movement of the wall 68 is permitted due to the provision of slot 69 in which the rivet 70 is received. There is thus provided a spring bottom having a pivoted rear section and formed with complementary mattress retaining means.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawings is to be interpreted as illustrative and not in a limiting sense.

Having thus described my invention, I claim as new and desire to secure by Letters Patent:—

1. A spring bottom comprising a front section and rear section pivoted thereto and adapted to be moved into inclined position, complementary mattress retaining means on the upper edges of said sections, said means comprising a member on one of said sections having a tubular frame and a frame member on the other section, and a rod attached to said second frame and slidably received within said tubular member.

2. A spring bottom comprising two complementary sections, each section having a lower frame portion and an upper frame portion, and foundation springs interconnecting said upper and lower frame portions, the adjacent ends of the upper frame portions being interpivoted, and means for retaining a mattress on said spring bottom against shifting, comprising a pair of three sided complementary upstanding walls attached to the upper frame portions, respectively, said upstanding walls comprising parallel wires interconnected by woven reed.

3. A spring bottom comprising two complementary sections, each section having a lower frame portion and an upper frame portion, and foundation springs interconnecting said upper and lower frame portions, the adjacent ends of the upper frame portions being interpivoted, and means for retaining a mattress on said spring bottom against shifting, comprising a pair of three sided complementary upstanding walls attached to the upper frame portions, respectively, said upstanding walls comprising parallel wires interconnected by woven reed, and means for interconnecting the adjacent ends of said walls.

MAX GURSKY.
